RAINCOAT

Byron Robbins, Stamford, Conn.

Application May 9, 1946, Serial No. 668,512

1 Claim. (Cl. 2-87)

1
This application relates to a coat, and more particularly to a raincoat designed to be waterproof and easily manufactured.

It is the object of this invention to contribute to the art a raincoat formed from a minimum number of parts, and with the seams so located as to minimize possible leakage.

One feature of the invention whereby the results thereof are obtained, resides in the forming of the raincoat from two main elements, with each element having one part forming one-half the front of the coat while another part thereof forms one-half the back of the coat, the portion connecting the two parts forming the shoulder of the coat and having extending therefrom a sleeve forming part.

The broad problem that I have attempted to solve through my invention has been attacked by a considerable number of inventors, many of whom have obtained patents on the results of their labor. Thus, cape-like garments have been formed having integral front and rear portions connected by shoulder portions, but such garments have not been successful because they were incapable of use as a full raincoat of conventional style. In such cases where an attempt was made to adapt such garments to conventional raincoat styles, considerable difficulty was encountered and a considerable number of parts were required. My invention makes it possible to form a raincoat from a minimum of parts with a minimum of seams, while at the same time permitting the shaping of the garment along conventional lines.

I have thus outlined the general nature of my invention and its relation to the prior art in order that the description thereof that follows may be better understood, and in order that my contribution to the art may be better appreciated. There are, of course, additional features of my invention that will be described hereinafter and which will form the subject of the claims appended hereto. Those skilled in the art will appreciate that the conception of which my disclosure is based, may readily be utilized by those skilled in the art as the basis for the designing of other structures for carrying out the several purposes of my invention. It is important, therefore, that the claim to be granted me shall be of sufficient breadth to prevent the appropriation of my invention by those skilled in the art.

Referring now to the drawings, Fig. 1 is a front view of a raincoat embodying my invention. Fig. 2 is a view showing the two main elements used to form the coat of Fig. 1. Fig. 3 is a diagrammatic

2
view showing just how each of the elements of Fig. 2 is draped to form the coat. Fig. 4 is a view showing the sleeve of the coat of Fig. 3 raised, and a gusset sewed to the sleeve and the front and back parts of the coat. Fig. 5 is a rear view showing a modified form of back utilizing a different pattern. Fig. 6 is a view of one of the elements utilized in making the coat of Fig. 5, while Fig. 7 shows a gusset used in the coat of Fig. 5. Fig. 8 is a view of the back element for the coat of Fig. 5.

Referring now more particularly to the drawings, and especially to Figs 1, 2, 3, and 4, the coat C of my invention is formed of two elements 10 best illustrated in Fig. 2. Each of these elements is formed with what I call a front part 11, a back part 12, and a sleeve part 13. For the securing of the collar, each element 10 is cut out at 14 as will be understood by those skilled in the art. 15 The collar used with the coat is conventional and the manner in which it is secured to the elements 10 does not form part of my invention. Incidentally, one of the elements 10 may have its front portion 11 formed somewhat differently 20 from that of the other in the event overlapping of more than a predetermined degree is required.

Referring now more particularly to Fig. 3, it will be noted that each element 10 may be draped as shown, with the part 11 forming the front of 30 the coat and the part 12 forming the back of the coat. The edges 11a and 12a will then be sewed or otherwise secured from the lower hem toward the point 15 at the armpit with the same continuing at 13a to form the sleeve 13. A suitable 35 substantially triangular gusset 16 will be utilized to form the armpit shown best in Figs. 2 and 4 at each side of the coat, coacting with the sleeve part 13 and with the two meeting edges 11a and 12a. This gusset 16 is set into a generally 40 V-shaped cut away portion 17 between the sleeve part 13 and the back part 12, and is sewed to the sleeve, the back part and the front part whereby to give proper shape to the garment and fit to the sleeve.

45 Each element 10 will of course be secured to the other element 10 to form the back of the coat, and for this purpose the edges 12b of the two elements 10 will be sewed to one another.

In Fig. 2 the shape of the coat elements 10 is 50 outlined in relatively straight lines, as it was thought desirable not to confuse the invention by using curved lines such as would normally be used in the formation of a garment. Actually, the outlines of the two elements 10 may be curved to yield any shaped coat that may be desired. As

a matter of fact, this feature of the coat being adapted for shaping in a conventional manner, is extremely important and forms a valuable part of my contribution to the art. Those skilled in the art will now appreciate that my invention yields a raincoat in which the front and back of each side thereof are formed of one piece, so that the resulting shoulder is seamless and is integral with the sleeve. Furthermore, the sleeve seam 13a is under the sleeve, and extends toward and into the seam at the side of the coat formed by the union of the outer edges 11a, 12a of the front and back portions as best seen in Fig. 4.

Referring now more particularly to Figs. 5-8 inclusive, I show there a coat formed of two main elements and a back element. Each of the main elements is designated by reference numeral 20 and is formed with a front portion 21, a cape portion 22 and a sleeve portion 23. The coat is draped somewhat along the lines of Fig. 3, except that the cape portions 22 merely overlie a back portion 24 shown in Fig. 8, this back portion 24 being suitably secured to the under surface of each cape portion 22 of the two elements 20. Suitable gussets 25 are used much in the same manner as the gussets 16 of the first modification. It will be noted that the back of the coat of Fig. 5 is seamless, the dotted line 12c representing the seam formed by the union of the two edges 12b of the modification of Figs. 1, 2, 3, and 4.

I believe that the construction and advantages of my invention will now be apparent to those skilled in the art.

I now claim:

A raincoat comprising a pair of one piece elements each having a part forming one-half the front of the coat, a part forming one-half the back of the coat, and a third part forming a complete sleeve of the coat, the front forming part and the back forming parts being connected by a shoulder forming portion from which extends the said third or sleeve forming part, there being a generally V-shaped cut away portion between the said sleeve part and the said back part, each of said elements having the corresponding longitudinal edges of its front and back forming parts secured at the side of the coat formed thereby from the armpit down to the lower hem, and a gusset secured within said cut away portion to shape said armpit, and with one edge of the said gusset sewed to the sleeve forming part and a further edge sewed to the said front part, and with the third edge thereof sewed to said back part.

BYRON ROBBINS.
